FIG. 1 is a front elevational view of a coat showing my new design; the back being conventional;

FIG. 2 is an enlarged view of a portion of the collar and lapel on the right of FIG. 1; and

FIG. 3 is an enlarged fragmentary view showing the pocket on the right of FIG. 1.

The characteristic feature of my design resides in the combination on a coat of the pockets and the lapel and collar portions all as shown on the drawing.

I claim:

The ornamental design for a coat or similar article, substantially as shown and described.
